UNITED STATES PATENT OFFICE.

LOUIS SMITH, OF CHICAGO, ILLINOIS.

PAPER-PAD HOLDER.

1,109,708.

Specification of Letters Patent.

Patented Sept. 8, 1914.

Application filed April 23, 1913. Serial No. 763,078.

To all whom it may concern:

Be it known that I, LOUIS SMITH, a citizen of the United States, and a resident of Chicago, in the county of Cook and State of Illinois, have invented certain new and useful Improvements in Paper-Pad Holders; and I do hereby declare that the following is a full, clear, and exact description thereof, reference being had to the accompanying drawings, and to the characters of reference marked thereon, which form a part of this specification.

This invention relates to pad holders of that kind designed to hold a pad or block 15 of sheets of paper in a position convenient for writing thereon and to permit the sheets to be readily detached or torn from the pile or pad.

The invention consists in the matters 20 hereinafter set forth and more particularly pointed out in the appended claims.

I have shown in the drawings the adaptation of my improvements to a desk pad holder and also to a telephone pad holder, 25 but the invention may be otherwise applied.

As shown in the drawings:—Figure 1 is a perspective view of a desk pad holder embodying my improvements. Fig. 2 is a perspective view of the base of the holder shown in Fig. 1. Fig. 3 is a fragmentary detail illustrating one manner of fixing the resilient pad supporting plate to the base frame. Fig. 4 is a fragmentary detail to 35 be hereinafter described. Fig. 5 illustrates the application of my improvements to a telephone pad holder.

Referring first to the construction shown in Figs. 1 to 4, inclusive, or the adaptation 40 of the invention to a desk pad holder, 10 designates, as a whole, the base or frame and 11 designates the spring pad supporting plate which directly supports the block or pad of sheets 12. The base or frame 10 may 45 be, as is herein shown as, made of a single piece of sheet metal cut and swaged into form. The piece of sheet metal from which the base is formed is bent downwardly at its margin to produce the oblique side and end walls 14, 15. The front part of the top wall of the hollow base thus produced is inclined at 16 with respect to the horizontal portion 17, and said inclined portion of the top wall is provided with openings 18. The 50 rear end of the top wall of the base is cut

out and is bent up about its integral rear margin to provide at the rear end of the device an upstanding member 19, the margin of which is provided with down-turned spurs or teeth 20 which bite into the pad 60 which is pressed thereagainst by the spring plate 11. Preferably the member 19 is turned over throughout its width to provide at 21 a narrow horizontal ledge to receive advertising matter. 65

The pad supporting plate may be made of spring metal. As herein shown, it is attached at its forward end to the inclined portion 16 of the top wall of the base and extends at its rear end beneath the overhanging spurs or teeth 20 of the upstanding member 19. The said plate may be attached to the inclined portion 16 of the upper wall of the base in any suitable manner, as by means of integral spurs 22 (Fig. 70 75 3) formed from the plate and extended through the openings 18 and clenched beneath the top wall of the base. The spring or resilient pad supporting plate when thus attached to the inclined portion of the top 80 wall of the base tends to rise at its rear end toward the teeth or projections 20 of the upstanding flange 19, but it is permitted to yield downwardly about the fulcrum line 85 23 between the inclined portion 16 and the horizontal portion 17 of the base.

To insert a pad in the holder the pad is placed on the resilient plate 11 and the rear end of the plate depressed to permit the pad to be slid under the overhanging spurs 20. 90 The plate is then released and the resiliency of the plate forces the pad toward the teeth or spurs 20 and said teeth or spurs coact with the resilient plate to hold the pad in plate while permitting the individual sheets 95 to be readily torn therefrom.

In order to prevent the points of the teeth or spurs 20 from being dulled or bent when only a few sheets of paper, or no sheets, are in the holder, the rear end of the spring pad supporting plate is provided with openings 100 24 which receive the points of the teeth or spurs when the plate occupies its uppermost position, as shown in Fig. 4.

In Fig. 5 I have shown my improved pad holder as applied to a telephone attachment to hold a pad or block in convenient position for entering memoranda thereon. As shown in said figure, 25 designates the shaft of the telephone to which the holder is at- 105 110

tached. The holder comprises a base 26, having at its forward end an inclined portion 27 to which the resilient pad holding plate 28 is attached, in the same general manner as in the construction before described. Said base is provided at its rear end with an upstanding portion 29 which is provided at its upper edge with an overhanging portion 30 having at its margin 10 downwardly pointed prongs or teeth 31 which bite into the upper sheets of the pad supported on the plate 28 in the manner before described. The said holder is attached to the shaft of the telephone by any 15 suitable form of clip 32.

In both forms of the pad holder the spring urged pad holding plate should be made slightly wider than the base, as best shown in Fig. 1, in order to permit the side margins thereof to be grasped by the thumb and fingers to manipulate the plate:

The holder described reliably holds the individual sheets of a block or pad while permitting them to be readily detached or 20 torn off from the pad when desired. Moreover, the holder permits the use of each 25 entire sheet of paper either for writing purposes or for advertising purposes, if it be desired to use the sheets for advertising, no 30 stub being left after the sheets are used, such as occurs where the sheets are clamped 35 between a base and a clamping member having a continuous biting edge. The space 30 may be occupied by permanent advertising matter.

In the construction shown in Figs. 1 to 4, inclusive, the side and end walls 14, 15 respectively, of the base constitute surfaces to receive permanent advertising matter, so 40 that it becomes unnecessary, in order to realize the full advertising value of the device, for the person furnishing the holder to subsequently furnish the blocks or pads to be used therewith. In other words, plain or 45 unprinted pads may be employed without

detracting from the value of the advertising feature of the device.

It will be understood that slight variations may be made in the structural details without departure from the spirit and scope 50 of the invention, and the invention is not limited to the details illustrated except as hereinafter made the subject of specific claims or as imposed by the prior art.

55 I claim as my invention:—

1. A holder for a pad of paper sheets comprising a sheet metal base provided at its rear end with an upstanding member having at its upper margin near the ends of said upstanding member integral, laterally spaced, down turned teeth to engage the upper sheets of the pad near their margins only, said base being formed at its forward end with a forwardly and downwardly inclined surface, and a pad supporting spring 60 plate attached to the base at said inclined forward portion thereof and extending upwardly and rearwardly therefrom with its rear end beneath said teeth, and between the rear end of which and said teeth a paper 65 pad is adapted to be confined.

2. A paper holder comprising a base provided with a top wall, said wall having at its forward end an oblique portion, said top wall being cut away at its rear portion and 70 the cut away portion being turned upwardly and provided at its margin and near its ends with depending teeth, and a pad supporting plate attached to the oblique portion 75 of the top wall and urged by its resiliency at its rear end toward said teeth.

In testimony, that I claim the foregoing as my invention I affix my signature in the presence of two witnesses, this 15th day of April A. D. 1913.

LOUIS SMITH.
